ADOLPH FISCHER, OF WEIMAR, GERMANY.

STAMP-AFFIXING DEVICE.

1,108,729.

Specification of Letters Patent. Patented Aug. 25, 1914.

Application filed November 11, 1913. Serial No. 800,380.

To all whom it may concern:

Be it known that I, ADOLPH FISCHER, a subject of the German Emperor, residing at Weimar, Grand Duchy of Saxe-Weimar, 5 Eisenach, Germany, have invented certain new and useful Improvements in or Relating to Stamp-Affixing Devices, of which the following is a specification.

My invention relates to a device for affixing stamps, in which the band of stamps coming from a roller is guided over a drum, and the stamp to be affixed is pressed in position by depressing a plunger after the gummed side of the stamp has been automatically moistened.

According to my invention, the drum over which the strip of postage stamps is guided, is mounted for rotary movement only; that is to say, no vertical movement takes place, 20 but the plates constituting the sides of the drum are radially movable and exposed to the action of the plunger in such a manner that when the latter is depressed, the lowermost plate with the stamp thereon is 25 brought in an exactly vertical manner on to, for instance, an envelop, and pressed upon it. The radially movable plates, which are normally drawn by springs or other elastic means toward the spindle of the drum, are 30 provided with teeth on their rear side (with reference to the rotation of the drum), while on the edges of the drum itself are arranged fixed rakes; so that when the plunger is depressed, the stationary rakes hold fast the 35 remainder of the strip of stamps, while the teeth on the then lowermost plate separates the postage stamp when the plate is depressed, without a separate cutting off device being required.

40 An embodiment of my invention is illustrated in the accompanying drawing, in which—

Figure 1 is a side elevation. Fig. 2 is a view from the same side as Fig. 1, but with 45 the frame wall removed. Fig. 3 is a section on line A B of Fig. 1. Fig. 4 shows the drum in front elevation, partly in section.

In the lower portion of the frame 1 is mounted a pentagonal drum 3 rotatable 50 about the spindle 2, the surface of the said drum being formed of plates 4 of a length equal to that of a postage stamp. These plates are held in position on the circumference of the drum by springs 5. Between the 55 plates 4, on the longitudinal edges of the drum 3 rakes 6 are provided, the teeth of

which coincide with the perforations of the postage stamp strip 15. Each of the plates 4 is provided at its rear edge (in the direction of rotation of the drum) with a rake 7, 60 the teeth of which coincide with those of the rakes 6, so that the teeth of two adjoining rakes 6, 7 can jointly pass through the corresponding series of holes in the strip. The roller 8, with the strip of stamps wound 65 thereon, is pushed over a roll 9 provided at the side of the frame 1, and is held on the said roll by friction by a spring 10 with which the latter is provided. The roll 9, rotatable about the spindle 11, is controlled 70 by a weak drag spring which gives a certain inertia to the roll during the unwinding of the strip. The strip 15 passes over a guide roller 12 and then over the circumference of the pentagonal drum 3. The teeth of a rake-like drag spring 14, pressed by the spring 13 against the circumference of the drum, 75 engage between the teeth of the rakes 6 and 7, and thus insure correct engagement of the said rake teeth with the perforations of 80 the stamp strip.

In the frame 1 is arranged a vertically movable plunger 18 which is provided with a handle 16 and is normally held in raised position by a spring 17; the vertical arms 19 85 of the said plunger passing in front of the ends of the drum 3. These arms 19 are provided at their lower ends with projections 20, which extend toward the interior of the drum, and when the plunger is depressed, 90 the said projections will engage the ends of the then lowermost plate 4, and will force that plate outwardly of the drum 3 in opposition to the action of the springs 5, and press it against the support. 95

The plunger 18 is provided with lateral pins 21 which extend into vertical guide slots 22 in the sides of the frame 1. During the depression of the plunger 18, one of the pins 21 acts on a lever 24 pivoted at 23 100 to the outer side of the frame, so that the lower arm of said lever swings toward the left, Fig. 1, against the action of the spring 25, and in that way, by means of a pawl 26 pivoted to its lower end and acting on a ratchet wheel 27 secured to the spindle 2 of the drum 3, advances the latter one fifth of a revolution. A spring pawl 28 secured to the frame 1 and engaging with said ratchet wheel 27, prevents the drum 3 from 105 turning back again. After the depression of the plunger 18 and consequent advance 110

of the drum 3 in the manner described, the lever 24 is held in its position by the spring-pressed pawl 29 which engages the upper end of said lever and remains so engaged until lifted by the pin 21 when the plunger completes its ascent. Lever 24 is then automatically returned by spring 25 into position to again effect rotation of the drum, but until the release of pawl 29 takes place, it is locked against return movement, as will be understood, and in this way, the drum 3 is prevented from rotating during the upward movement of the plunger.

When using the device, the end of the postage stamp strip 15 is unwound from the roller 8, led over the guide roller 12, and introduced between the rake plate 14 and the adjacent edge of the drum 3, so that the rake teeth 6 and 7 of the drum edge engage with the perforations in said strip, while the teeth of the rake-plate 14, being situated between the said teeth 6 and 7 tend to press the strip against the drum. This introduction of the postage stamp strip can be easily effected, as the corresponding side of the drum 3 can be uncovered by rocking the hereinafter-described tank 38 away from said drum, said tank being hinged at 39 to the frame.

The operation of the device is as follows: When the plunger 18 is depressed by the handle 16, the lever 24 is first actuated, the pin 21 sliding along the curved edge 41 of the said lever. In that way, the drum 3 is advanced one step by the pawl 26 and ratchet wheel 27. The pawl 28 then locks the drum 3 in the new position, while the pawl 29 at the same time engages behind the upper end of the lever 24, so that the latter is locked during the further descent as well as during the subsequent ascent of the plunger. During the advance of the drum 3, the latter has unwound the strip 15 to the extent of one stamp by means of the teeth 6, 7 on its sides, and the first stamp of the strip is now under the lowermost plate 4 of the drum. During the further descent of the plunger 18, the pins 21 act on the curved edges 33 of the pair of levers 31, which operate the moistening device. These levers are pivoted at their upper ends 31' and have their lower ends enlarged and formed with slots 31² for the reception of the reduced ends or trunnions of the perforated, hollow moistener roller 31³, the latter being connected at one of its ends with tank 38 by means of a flexible tube or pipe 31⁴, which communicates with the bottom of said tank. The arrangement is such, therefore, that the levers 31 are caused by the action of pins 21 against their edges 33 to swing toward spindle 2, as will be understood from Fig. 1, thereby carrying with them, in the same direction, the roller 31³, which is kept constantly moistened by

reason of its connection with tank 38 and which, in consequence, moistens the gummed face of the stamp, the said roller being drawn upward toward the drum by the action of the springs 31⁵. The lower ends 20 of the arms 19 of the plunger have in the meantime reached the said plate 4, so that the latter, during the further descent of the plunger, is moved away from the drum 3, the rake 7 provided on the rear edge of 75 the plate, tearing off the stamp from the strip 15, the said stamp then being pressed and stuck on the support as the plate 4 continues to descend. When the affixing of the stamp is completed, the plunger 18 is allowed to rise under the action of the spring 17, the plate 4 first returning to its original position on the circumference of the drum 3, whereupon the levers 31 with the moistening roller 31³ are returned by the spring 42 to their original position, and finally, on completion of the ascent of the plunger 18, the pawl 29 is disengaged, so that the lever 24 can return to its position ready for use under the action of the spring 25, 90 and the whole device is ready for use again.

What I claim is:

1. In a stamp-affixing device, the combination, with means for supporting a perforated strip of stamps; of a drum over which the strip passes having counterpart, radially-movable plates constituting the circumference thereof; means for rotating the drum; co-operating strip-feeding means provided upon said plates and the longitudinal edges 100 of the drum for engagement in the perforations in said strip during the rotation of said drum; and means for depressing the lowermost plate after each rotation of the drum, to sever the stamp carried thereby 105 from said strip.

2. In a stamp-affixing device, the combination of a strip-feeding drum having counter-part, radially-movable stamp-applying plates constituting the circumference thereof; means for imparting a step-by-step rotary movement to the drum; and means for depressing the lowermost plate after each 110 rotation of said drum.

3. In a stamp-affixing device, the combination of a strip-feeding drum having counterpart, radially-movable stamp-applying plates constituting the circumference thereof; means for imparting a step-by-step rotary movement to the drum; and a depressible element provided with means for actuating the first-named means during its downward movement and with additional means for depressing the lowermost plate at the 120 conclusion of such movement.

4. In a stamp-affixing device, the combination of a strip-feeding drum having counterpart, radially-movable stamp-applying plates constituting the circumference thereof; lever-operated means for imparting a 130

step-by-step rotary movement to the drum; and a depressible element provided with a pin for actuating the first-named means, and with inwardly-projecting means arranged to 5 engage and depress the lowermost plate at the conclusion of such movement.

5. In a stamp-affixing device, the combination, with means for supporting a perforated strip of stamps; of a drum over 10 which the strip passes having counterpart, radially-movable plates constituting the circumference thereof; means for rotating the drum; coöperating series of rake teeth provided upon the rear edges of said plates and 15 between the adjacent edges of successive plates, for engagement in the perforations in the said strip, to feed the latter during the rotation of the drum; and means for depressing the lowermost plate after each rotation 20 of the drum, to sever the stamp carried thereby from said strip.

6. In a stamp-affixing device, the combination, with means for supporting a perforated strip of stamps; of a drum over 25 which the strip passes having counterpart, radially-movable plates constituting the circumference thereof; means for rotating the drum; coöperating strip-feeding means provided upon said plates and the longitudinal 30 edges of the drum for engagement in the perforations in said strip during the rotation of said drum; a spring rake acting upon

said coöperating strip-feeding means, to insure the engagement of the latter in said perforations; and means for depressing the 35 lowermost plate after each rotation of the drum, to sever the stamp carried thereby from said strip.

7. In a stamp-affixing device, the combination, with means for supporting a perforated strip of stamps; of a drum over 40 which the strip passes having counterpart, radially-movable plates constituting the circumference thereof; means for rotating the drum; coöperating series of rake teeth provided upon the rear edges of said plates and 45 between the adjacent edges of successive plates, for engagement in the perforations in the said strip, to feed the latter during the rotation of the drum; a spring rake having its teeth arranged between said coöperating series of teeth, to insure their engagement 50 in said perforations; and means for depressing the lowermost plate after each rotation of the drum, to sever the stamp carried 55 thereby from said strip.

In testimony whereof I have hereunto set my hand in presence of two subscribing witnesses.

ADOLPH FISCHER.
